UNITED STATES PATENT OFFICE.

CHARLES H. JOHNSEN, OF HARVEY, ILLINOIS.

EXTENSION-TABLE.

1,031,557.

Specification of Letters Patent. Patented July 2, 1912.

Application filed March 19, 1910. Serial No. 550,341.

To all whom it may concern:

Be it known that I, CHARLES H. JOHNSEN, a citizen of the United States, residing at Harvey, county of Cook, and State of Illinois, have invented certain new and useful Improvements in Extension-Tables, of which the following is a specification.

My invention relates to improvements in extension tables and especially to the type 10 of table set forth in my prior Patent No. 907,503, dated December 22nd, 1908.

The object of the invention is to provide an extension table of improved construction and operation and the invention consists in 15 the combination and arrangement of parts hereinafter described and claimed.

The invention will be best understood by reference to the accompanying drawings forming a part of this specification, and in 20 which—

Figure 1 is a longitudinal section through the top of the table in extended form, Fig. 2, a bottom plan view of Fig. 1 with certain parts removed and others broken away, Fig. 25 3, a longitudinal section of the top portion of the table when in folded position, Fig. 4, a partial bottom plan view corresponding to Fig. 3 but with portions broken away, Fig. 5, a detail section illustrating the construction for mounting the table extension leaves, Fig. 6, a section on line $x-x$ of Fig. 4, Fig. 7, a perspective view illustrating an operating lever for the extension leaves, Fig. 8, a perspective view illustrating the support 30 for the extension leaves when in extended position, and Fig. 9, a sectional elevation illustrating the extension leaf support and the construction for securing certain of said leaves from lateral displacement.

40 The preferred form of construction as illustrated in the drawings comprises two table top portions 1 and 2 adapted to unite to form a circular table top and provided with the downwardly extending rims or flanges 3 and 4 respectively. Fixed to the top portions 2 are guide rods 5 secured in brackets 6 and telescoping two guide tubes 7 fixed to the top portion 1 in brackets 8. The free ends of tubes 7 are supported in 45 brackets 9 having base flanges 10 slidable in grooves 11 in the bottom of top portion 2. Flanges 10 are held in grooves 11 by means of securing plates 12 secured to the bottom 50 of portion 2 and overlapping the outer portions of said slots. A threaded shaft 13 is mounted on top portion 1 and is provided

with a square end 14 adapted to be engaged by a crank handle 15 for rotating said shaft. The other end of shaft 13 takes into a threaded tube or sleeve 16 secured in a 60 bracket 17 attached to table portion 2.

A slideable member 18 is slidably secured to the bottom of table portion 1 by means of guides 19 as shown. Member 18 is provided at either side with lugs 20 carrying pivot 65 studs 21 to which operating levers 22 are pivoted. At their free ends levers 22 are connected with a supporting plate 23 slidably secured by means of guides 24 to the bottommost leaf 25 of the extension leaves. 70 Three extension leaves are provided with leaves 26 and 27 arranged one above the other and on leaf 25 when the table is in folded position. Leaves 26 and 27 are provided with grooves 11', in alignment with 75 grooves 11 in table portion 2 when said leaves are in operative positions. Plates 26' and 27' secured to the bottoms of leaves 26 and 27 serve to prevent removal of said leaves from brackets 9. Each of the leaves 80 26 and 27 carries projecting pins 26'' and 27'' adapted to engage in corresponding sockets in table portion 2 and leaf 27 to prevent lateral movement of said leaves when in operative positions. Brackets 28 are secured to plate 23 at either side and are slidably mounted on guide pins 29 secured to the adjoining ends of guide member 18. Springs 30 mounted upon pins 31 on member 18 and in recesses 32 in brackets 28 85 serve to balance the weight of the extension leaves on said bracket and prevent binding of the bracket on the guide pins. The levers 22 are connected to brackets 28 by means of links 22' which permit of opera- 90 tion of said levers and sliding of plate 23. The lower edges of levers 22 are provided with cam surfaces 33, 34 and 35 and bearing surfaces 36. A spring 38 secured to pin 39 on member 18 and to pin 40 on the bottom 95 of table portion 1 serves to yieldingly press member 18 and levers 22 toward the extension leaves.

A lever 41 is pivoted at 42 to the bottom of table portion 1, one end having a slot and pin connection 43 with member 18 and the other end having a slot and pin connection 44 with a lever 45 pivoted at 46 to the bottom of table portion 1.

Secured to the bottom of table portion 1 110 is a segmental plate 46' having locking recesses 47 adapted to receive a locking pro-

jection 48 on the bottom of lever 45. The outer end of lever 45 is turned downwardly along the inner side of rim 3 and is provided with a finger projection 49 by means 5 of which the same may be manipulated.

Secured to the end of threaded tube 16 is a bracket 50 carrying flanged rollers 51 arranged to ride upon the bottom edges of levers 22.

- 10 By the construction as above set forth it will be seen that upon rotation of shaft 13 table portions 1 and 2 may be forced apart or drawn together as desired. When in folded position, it will be observed that the 15 inner end of the member 18 normally rests against extension leaf 27 and that upon separation of table members 1 and 2, the extension leaves remaining stationary, the member 18 will be given an initial sliding movement 20 by the action of spring 38 until lugs 20 thereon contact with the ends of guides 19, after which member 18 will normally move with the top member 1. As the table portions are farther separated rollers 51 contact 25 with cam surfaces 33 causing the elevation of the pile of extension leaves until the uppermost leaf 27 comes flush with the top of the table, there being sufficient opening between the table portions at this time 30 to permit of this. Should it now be desired to lock the table in position with an extension of but one leaf, the lever 45 is actuated to draw member 18 so that rollers 51 will be well advanced upon the corresponding bearing surfaces 36 of levers 22. These surfaces serve as positive supports 35 and locks for rollers 51, thus preventing depression of leaf 27 and permitting the table portions to be drawn together to a nice fit with said leaf. Depressions 47 and projection 48 serve as a convenient means 40 for temporarily holding lever 45 in locking or unlocking positions. If more extension leaves are desired, locking lever 45 is thrown 45 to unlocking position whereupon table portions 1 and 2 may be further separated until cam surfaces 34 serve to elevate the next extension leaf 26, the first extension leaf 27 being in the meantime held from lateral displacement by the engagement of locking pins 27'' with a corresponding socket in plate 12 and table portion 2 as illustrated in Fig. 9. If desired this leaf 50 may be locked in position as before or the third leaf 25 may be elevated to operative position by the action of cam surfaces 35 and locked as before, the base flanges 10 on brackets 9 passing into grooves 11' in leaves 26 and 27 after elevation.
- 60 Table portions 1 and 2 are mounted upon a suitable pedestal 52 by means of a bracket 53 having bearings 54 and 54' slidably engaging tubes 7 and brackets 9. A shaft 55 oppositely threaded to shaft 13 is mounted 65 in a bearing 56 on table portion 1 and given

a threaded connection with a nut 57 carried by a bracket 58 on supporting bracket 53. Shaft 55 carries pinion 59 meshing with a pinion 60 upon shaft 13. By this construction it will be observed that upon rotation of shaft 13 to cause separation of the table portions, shaft 55 will operate to cause movement of pedestal 52 relatively to top portion 1. The pitch of the threads on said shafts and the size of the intermeshing 70 gears is such that the relative movement of pedestal 52 will just compensate for the movement of table portions 1 and 2 thus maintaining the pedestal stationary and causing the top portions to arrange themselves symmetrically with relation to said pedestal. Thus the pedestal will always remain under the center of the table.

While I have illustrated and described the preferred construction for carrying my 85 invention into effect this is capable of variation and modification without departing from the spirit of the invention. I therefore do not wish to be limited to the exact details of construction set forth but 90 desire to avail myself of such variations and modifications as come within the scope of the appended claims.

Having described my invention what I claim as new and desire to secure by Let- 95 ters Patent is:

1. An extension table comprising two top portions arranged to be moved toward and away from each other; a plurality of leaves arranged beneath said top portions; means for successively placing said leaves in operative positions as the top portions are moved apart; a pedestal slidably supporting each of said top portions; a threaded shaft mounted on one of said top portions and threaded in a member fixed to the other; an oppositely threaded shaft carried by said shaft bearing portion and threaded in a member attached to said pedestal; and intermeshing gears on said shafts, substantially as described.

2. An extension table comprising two top portions arranged to move toward and away from each other; a plurality of leaves arranged beneath said top portions; a member slidably mounted on one of said top portions; a lever pivoted to said slidably member and having its free end slidably and pivotally connected with one of said leaves; said lever having a cam shaped lower edge; and means for shifting said slidable member to shift said cam to locking position, substantially as described.

3. An extension table comprising two top portions arranged to move toward and away 125 from each other; a plurality of leaves arranged beneath said top portions; a member slidably mounted on one of said portions, a spring arranged to cause an initial movement of said slidable member; a stop limit 130

ing this initial movement; a lever pivoted to said slidable member and having its free end slidably and pivotally connected with one of said leaves, said lever having a cam shaped lower edge; and means for shifting said slidable member to shift said cam edge to locking position, substantially as described.

4. An extension table comprising two top portions arranged to move toward and away from each other; a plurality of leaves arranged beneath said top portion; a member slidably mounted on one of said portions; a pair of levers pivoted to said slidable member and having their free ends slidably and pivotally connected with one of said leaves, said levers having cam shaped lower edges; and means for shifting said slidable member to shift said cam edges to locking positions, substantially as described.

5. An extension table comprising two top portions arranged to move toward and away from each other; a plurality of leaves arranged beneath said top portions; a member slidably mounted on one of said portions; a spring arranged to cause an initial movement of said slidable member; a stop limiting this initial movement; a pair of levers pivoted to said slidable member and having their free ends slidably and pivotally connected with one of said leaves, said levers having cam shaped lower edges; and means for shifting said slidable member to shift said cam edges to locking positions, substantially as described.

6. An extension table comprising two top portions; guide rods fixed to one of said portions and telescoping guide tubes fixed to the other; a pedestal slidably supporting said guide tubes; a threaded shaft mounted on one of said portions and threaded into a tube fixed to the other; an oppositely threaded shaft geared to said first mentioned shaft and having threaded connection with said pedestal; a plurality of leaves arranged beneath said top portions; and means for successively placing said leaves in operative positions as the top portions are moved apart, substantially as described.

50 7. An extension table comprising two top

portions; guide rods fixed to one of said portions and telescoping guide tubes fixed to the other; a pedestal slidably supporting said guide tubes; a threaded shaft mounted on one of said portions and threaded into a tube fixed to the other; an oppositely threaded shaft geared to said first mentioned shaft and having threaded connection with said pedestal; a plurality of leaves arranged beneath said top portions; a member slidably mounted on one of said portions; a spring arranged to cause an initial movement of said slidable member; a stop limiting this initial movement; a lever pivoted to said slidable member and having its free end slidably and pivotally connected with one of said leaves, said lever having a cam shaped lower edge; and means for shifting said slidable member to shift said cam edge to locking position, substantially as described.

8. An extension table comprising two top portions; guide rods fixed to one of said portions and telescoping guide tubes fixed to the other; a pedestal slidably supporting said guide tubes; a threaded shaft mounted on one of said portions and threaded into a tube fixed to the other; an oppositely threaded shaft geared to said first mentioned shaft and having threaded connection with said pedestal; a plurality of leaves arranged beneath said top portions; a member slidably mounted on one of said portions; a spring arranged to cause an initial movement of said slidable member; a stop limiting this initial movement; a pair of levers pivoted to said slidable member and having their free ends slidably and pivotally connected with one of said leaves, said levers having cam shaped lower edges; and means for shifting said slidable member to shift said cam edges to locking positions, substantially as described.

In testimony whereof I have signed my name to this specification in the presence of two subscribing witnesses.

CHARLES H. JOHNSEN.
